CLAIM

The ornamental design for a hand jack, as shown and described.

DESCRIPTION

FIG. 1 is a front-left-top perspective view of a hand jack according to my new design;

FIG. 2 is a rear-left-bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines in the drawings show portions of the hand jack that form no part of the claimed design.
